UNITED STATES PATENT OFFICE.

FOREST EDWARDS GOODMAN, OF WACO, TEXAS.

DESIGN FOR A STIRRUP.

SPECIFICATION forming part of Design No. 33,690, dated December 11, 1900.

Application filed June 23, 1900. Serial No. 21,382. Term of patent 7 years.

To all whom it may concern:

Be it known that I, FOREST EDWARDS GOODMAN, a citizen of the United States, residing at Waco, in the county of McLennan and State of Texas, have invented and produced a certain new and original Design for Stirrups; and I do declare the following to be a full, clear, and exact description of the invention, such as will enable others skilled in the art to which it appertains to make and use the same.

My invention relates to a new and original design for stirrups; and it consists of a design of the shape and configuration shown in the accompanying drawings, in which—

Figure 1 is a perspective view. Fig. 2 is a vertical sectional view, and Fig. 3 is a longitudinal sectional view through the cross-bar.

The leading features of the design consist in the stirrup-body of approximately U shape, the arms *a* of which are bowed or curved rearwardly and have their rear edges uniformly curved from *b* at or about the center of the tread or foot-piece to *c* and projecting vertically from *c* to *d*, while their forward edges are curved uniformly in a reverse direction from *e* to *f*, thence from *f* to *g* curved inwardly, and from *g* to *h* extend vertically, thus projecting the front edge of the tread or foot-piece outwardly and forwardly on a well-

defined swell from the points *f* to *f* and concaving the rear edge of the tread in like manner, and also causing the upper ends of said arms to stand straight and vertical, with their axes substantially in a line parallel with the vertical plane of the rear edge of the central portion of the tread or foot-piece. The straight and vertical upper ends of the arms *a* are connected by a tubular cross-bar *i*, while their outer sides are provided with longitudinally centrally-disposed ribs or swells *j*. Diaphragms *k* on the interior of the cross-bar *i*, at opposite sides of the center thereof, divide the bore of said bar to form end pockets *l*, opening outwardly at the ends of the cross-bar, and a central pocket *m* in open communication with a longitudinal slot *m'* in the upper side of said cross-bar.

What I claim is—

The design for a stirrup as herein shown and described.

In testimony whereof I have hereunto set my hand in presence of two subscribing witnesses.

FOREST EDWARDS GOODMAN.
